US00D787196S

(12) **United States Design Patent** (10) **Patent No.:** **US D787,196 S**
(45) **Date of Patent:** **** May 23, 2017**

(54) **HAIRBRUSH**

(71) Applicant: **Tangle Teezer Limited**, London (GB)

(72) Inventors: **Cameron Bruce William Treeby**,
London (GB); **Julian Lesley Meagher**,
London (GB)

(73) Assignee: **Tangle Teezer Limited**, London (GB)

(**) Term: **14 Years**

(21) Appl. No.: **29/489,614**

(22) Filed: **May 1, 2014**

Related U.S. Application Data

(62) Division of application No. 29/367,167, filed on Aug. 4, 2010, now Pat. No. Des. 703,956.

(57) **CLAIM**

The ornamental design for a hairbrush, as shown and described.

DESCRIPTION

FIG. 1 is a top view of a hairbrush;

FIG. 2 is a bottom view of the hairbrush of FIG. 1;

FIG. 3 is perspective view of the hairbrush of FIG. 1; and,

FIG. 4 is side view of the hairbrush of FIG. 1, the opposite side being identical.

The broken line showing of exemplary bristles throughout the drawing figures is for illustrative purposes only and forms no part of the claimed design.

1 Claim, 4 Drawing Sheets
